United States Patent Office

Des. 217,850
Patented June 23, 1970

217,850

BOTTLE

Edward H. Lawton and John R. Nelson, Toledo, Ohio, assignors to Owens-Illinois, Inc., Toledo, Ohio, a corporation of Ohio

Filed Mar. 21, 1969, Ser. No. 16,379

Term of patent 14 years

Int. Cl. D9—01

U.S. Cl. D9—100

FIG. 2

FIG. 1

FIG. 1 is an elevational view of a bottle embodying our new design, the side opposite that seen being the same in appearance as the side shown; and

FIG. 2 is a top plan view thereof.

We claim:

The ornamental design for a bottle, as shown and described.
